FLUID IRRADIATOR HOUSING

Felix R. Grat, Lake Hiawatha, and Thomas A. Vizzini,
Morris Plains, N.J., assignors to Radiation Machinery
Corporation, a corporation of New Jersey

Filed Apr. 9, 1969, Ser. No. 16,649

Term of patent 14 years

Int. Cl. D24—02

U.S. Cl. D83—1

Fig. 1

Fig. 2

Fig. 3

Fig. 4

FIG. 1 is a left front perspective view of a fluid irradiator housing showing our new design;

FIG. 2 is a left side elevational view thereof, the right side thereof being a mirror image of FIG. 2;

FIG. 3 is a top plan view thereof; and

FIG. 4 is a rear elevational view thereof.

We claim:

The ornamental design for a fluid irradiator housing, as shown and described.
